UNITED STATES PATENT OFFICE.

HENRY C. HELMS, OF INDIANAPOLIS, INDIANA, ASSIGNOR OF ONE-HALF TO EDGAR C. KREGLO, OF INDIANAPOLIS, INDIANA.

HEAT REGISTER AND CUT-OFF FOR AIR-HEATING SYSTEMS.

Application filed May 19, 1927. Serial No. 192,625.

This invention relates generally to registers for hot air heating systems and aims to provide a device of this character that is so constructed as to permit the heat to be directed into the room at various angles and also to provide means whereby the heat may be entirely or partially cut off whenever desired.

In carrying out the present invention there is provided a register including a register frame for disposition within a furnace floor heat box that is arranged within the house flooring and within which frame is arranged a grilled frame that has attachment with a collapsible pipe section of elbow formation when extended. The grilled frame being pivoted to the register frame so that the same may be swung upwardly to the desired position. When so swung in an upward direction the collapsible pipe section will be extended and will afford means for diverting the heat through the frame and this regardless of the position of the same with respect to the register frame.

Furthermore there is located within the lower end of the furnace floor heat box a control valve that may be operated at the floor surface to permit the heat to be totally or partially cut off.

One of the most important objects of this invention resides in the provision of a structure of this character that is extremely simple and highly efficient in operation and one that may be arranged within the flooring without requiring any alterations thereof other than that usually required in the installation of a hot air heat register.

In the drawings wherein like reference characters indicate corresponding parts:

Figure 1 is a fragmentary floor plant device within which is arranged my improved device.

Figure 2 is a detail section therethrough, the collapsible pipe section to which the grilled frame is attached being extended.

Figure 3 is a side elevation of the control valve unit per se.

Figure 4 is an enlarged fragmentary section through the collapsible elbow pipe section, and

Figure 5 is a fragmentary top plan view thereof.

Now having particular reference to the

drawings, A designates a building flooring provided with an opening within which is arranged a rectangular shaped furnace floor or heat box 5, within the upper end of which is arranged a similar shaped register frame 6 flanged at its upper edge as at 7 for overlapping the flange at the upper edge of the box 5 and the opening in the flooring as disclosed in Figures 1 and 2. Pivottally mounted at its forward edge within this register frame 6 by reason of pintles 8—8 at the opposite ends thereof is a grilled register frame 9. Arranged around the back and side edges of the register frame 6 at the inner side thereof and slightly beneath the upper side is a flange 10 for supporting the edge of the grilled frame 9 when the same is lowered into the frame 6.

The invention further consists of a collapsible pipe section 11 of elbow formation when extended, said collapsible pipe consisting of a plurality of similarly designed sections, each of which is designated 12. Each section consists of a back wall 13 and a pair of side walls 14, the back wall thereof being of curvilinear formation, while the opposite edges of the side walls taper inwardly toward the outer ends thereof as clearly indicated in Figure 2. From the inner to the outer sections, said sections are of gradually increasing area so that they may have overlapping relation as also indicated in Figures 2, 4, and 5. The rear edge of the innermost section 12 is flanged as at 15 for engaging beneath the interior flange of the register frame 6 to limit the outward swinging movement of the elbow pipe with respect to said register frame.

The outer ends of the side walls of all the sections 12 are pivotally connected to the forward edge of the grilled frame 9 beneath its surface as at 16 in Figure 2.

To limit the sliding movement of the sections with respect to each other, all of the sections with the exception of the innermost one are formed at their back walls and adjacent their opposite ends with slots 17—17 for receiving pins 18—18 upon the forward edges of the back walls of the next adjacent sections with the exception of the outermost section as in Figure 2.

The forward edge of the foremost section is riveted, bolted, or otherwise secured to the grilled frame 9 as at 19 so that when said

grilled frame is swung upwardly with respect to the register frame 6, the collapsible pipe section 11 will be extended.

Arranged within the innermost section 12 of this collapsible pipe is a cross strap 20 formed adjacent one end with a slot 21. Pivoted to the adjacent end of the grilled frame 9 is a curved latch lever 22, the outer edge of which is formed with spaced slots 23 for engagement with the forward end of the slot 21 in the strap 20. It being obvious from Figure 2 that the inner end of this latch lever is slidably arranged through the slot 21. Thus by raising the grilled frame to any one of four positions to extend the collapsible pipe section 11 it may be maintained in said position by engaging the proper notch 23 of the lever with the end of the slot 21 in the strap 20. The adjacent side of the register frame 6 is notched as at 24 so that the lever 22 may slide therethrough during the raising and lowering of the grilled frame 9. Furthermore, by swinging the lever 22 rearwardly, the frame may be lowered at will.

Arranged within the furnace floor or heat box 5 adjacent the lower end thereof, and which lower end portion 25 is of rounded configuration is a damper valve supporting ring 26 formed at opposed points and at its outer surface with bosses 27-27 that are arranged through opposed openings in the lower rounded end of said box 5. Loosely mounted through these bosses 27-27 are pintles 28-28 attached at opposed points to the periphery of a circular damper valve 29. One of these pintles 28 extends considerably outwardly of the box 5 and is equipped with a chain pulley 29'. Directly above this pulley 29' the box 5 is formed at its upper end with a pulley 30, the top of which extends through an opening 31 in the flange 7 of the register frame 6. Trained over these pulleys is an endless chain 32 and obviously by turning the uppermost pulley 31, the damper valve 29 may be opened or closed to the desired extent.

Having communication with the lower rounded end of the box 5 is the usual heat pipe 33.

It will thus be seen that I have provided a highly novel, simple and efficiently operating heat register and control valve that is well adapted for all the purposes heretofore designated, and even though I have herein shown and described the invention as consisting of certain detail structural elements it is nevertheless to be understood that some changes may be made therein within the spirit and scope of the appended claims.

Having thus described the invention, what I claim as new is:-

1. In a register construction for hot air heating systems, an open frame for disposition in a floor opening, a grilled frame pivoted at one edge within the first mentioned

frame and adapted for disposition therein or to be swung upwardly therefrom, and a collapsible elbow pipe section arranged between the frames and so associated therewith as to be extended when the grilled frame is raised. 70

2. In a register construction for hot air heating systems, an open frame for disposition in a floor opening, a grilled frame pivoted at one edge within the first mentioned frame and adapted for disposition therein or to be swung upwardly therefrom, a collapsible elbow pipe section arranged between the frames and so associated therewith as to be extended when the grilled frame is raised, and means for releasably locking the grilled frame and collapsible elbow pipe section in predetermined extended positions. 80

3. In a register construction for hot air heating systems, an open frame for disposition within a floor opening, a grilled frame pivoted at one end within the first frame and adapted for disposition therein, or to be swung upwardly therefrom, and a collapsible connection between the two frames to close the opening therebetween when the grilled frame is swung upwardly and to direct the heat through the grilled frame regardless of its swung position with respect to said open frame. 90

4. In a register construction for hot air heating systems, an open frame for disposition within a floor opening, a grilled frame pivoted at one end within the first frame and adapted for disposition therein, or to be swung upwardly therefrom, a collapsible connection between the two frames to close the opening therebetween when the grilled frame is swung upwardly and to direct the heat through the grilled frame regardless of its swung position with respect to said open frame, and means for maintaining the grilled frame in any predetermined raised position. 100

5. In a register construction for hot air heating systems, a register frame for disposition in a floor opening, a grilled frame pivoted at its forward edge within the register frame and adapted for disposition therein when in one position, a collapsible elbow pipe section, the sections thereof being operatively connected together, the lowermost section being provided with means to limit the upward movement of the lower section with respect to the register frame, the upper section being operatively connected to the grilled frame whereby said sections are extended when the grilled frame is raised, the sections being collapsed and confined within the register frame when the grilled frame is in its lowered position, and means for locking the grilled frame and the collapsible elbow pipe section in any predetermined raised position with respect to the register frame. 110

6. In a register construction for hot air heating systems, a floor box arranged within an opening in the floor, a register frame sup- 120

ported in the upper end of the box, a grilles frame pivoted at its forward edge within the register frame and adapted for disposition therein when in one position and capable 5 of being swung upwardly therefrom, a collapsible elbow pipe section arranged between the register frame and the grilles frame and so associated therewith as to be extended

when the grilles frame is raised, and to be collapsed and confined within the register 10 frame when the grilles frame is lowered, and a manually actuated damper arranged within the floor box below the register frame.

In testimony whereof I affix my signature.

HENRY C. HELMS.
